UNITED STATES PATENT OFFICE.

CHARLES SUTTER, OF SURESNES, FRANCE.

MUZZLE SUPPORT FOR AUTOMATIC GUNS.

Application filed February 27, 1922. Serial No. 539,516.

To all whom it may concern:

Be it known that I, CHARLES SUTTER, a citizen of the French Republic, residing at Suresnes, Seine, France, have invented 5 certain new and useful Improvements in Muzzle Supports for Automatic Guns; and I do hereby declare the following to be a full, clear, and exact description of the invention, such as will enable others skilled 10 in the art to which it appertains to make and use the same.

My invention relates to improvements in muzzle supporting attachments for automatic guns.

Such guns are more or less heavy and while they may be fired, when emergency requires, from the shoulder with the soldier standing erect, it is generally preferable, whenever practicable, to fire lying down, at 20 which time not only is the greater proportion of the weight of the piece taken on the muzzle support, but the soldier may aim better and more continuously, and he also presents a much smaller and less conspicuous target to the enemy.

Such supports have hitherto generally been provided with pointed legs which, when the ground is soft or muddy, tend to stick into the ground and disturb the line 30 of sight, and also in a large measure prevent the gun from recoiling in the line of fire.

My present invention is intended to provide a light and efficient supporting arrangement which may be quickly attached to or 35 removed from the piece, and in which the supporting legs are provided with light rounded shoes having considerable bearing surface which will not only support the piece on soft ground, but will also permit 40 the recoil of the piece in the line of fire.

My present invention is also especially intended to cover certain features shown, but not claimed, in my pending application entitled Improvements in automatic machine 45 guns, filed March 25, 1921, Ser. No. 455701, and also to cover certain improvements on the structure shown in the application aforesaid.

My invention will be more fully understood after reference to the accompanying drawings, in which like parts are indicated by similar reference symbols throughout the several views, and in which:

Figure 1 shows a side elevation of the 55 gun in use by the soldier, the latter being

shown in the recumbent position, and being indicated in dotted lines.

Figure 2 is a front elevation of a larger scale of the supporting attachment shown in Fig. 1, the gun itself being shown in dotted lines.

Figure 3 is a plan view of a portion of the gun barrel with the supporting attachment in the operative position, the parts being shown on a somewhat smaller scale than in Fig. 2, but on a larger scale than in Fig. 1.

Figure 4 is a side elevation of the parts shown in Fig. 3, but with the supporting legs and shoes swung up alongside the barrel and showing in dotted lines the position for transporting same with the gun.

Figure 5 is a detail showing the upper portion of the supporting attachment detached from the gun, the supporting legs 75 being indicated in dotted lines.

Figure 6 is a view of the parts shown in Fig. 5 as seen from the left of said figure, the gun barrel being indicated in dotted lines.

Figure 7 is a similar view to Fig. 6, but shows the right hand head piece and corresponding leg removed, and said figure shows the socket piece in engagement with the trunnions.

Figure 8 shows a section along the line 8-8 of Fig. 6, and looking in the direction of the arrows, parts being shown in elevation.

Figure 9 shows a section along the line 90 9-9 of Fig. 6, and looking in the direction of the arrows.

Figure 10 is a detail showing the trunnion band detached from the gun.

Figure 11 is an end view of the trunnion band as seen from the left of Fig. 10.

Figure 12 is a side elevation of the head piece for the left-hand leg.

Figure 13 is a view of the piece shown in Fig. 12 as seen from the left of said figure.

Figure 14 is an end view of the socket piece which is pivoted to the head piece and engages the trunnion.

Figure 15 shows a section along the line 105 15-15 of Fig. 14, and looking in the direction of the arrows.

Figure 16 is a front elevation of a modified form of supporting attachment; the gun being indicated in dotted lines.

Figure 17 is a view of the device shown 110

in Fig. 16, as seen from the left of said figure; and

Figure 18 shows a section along the line 18—18 of Figure 17 and looking in the direction of the arrows.

A represents the gun provided with the usual barrel B, with any suitable removable front sight C. Mounted on this barrel, near the muzzle thereof, is a trunnion band D which may be locked in the desired position on the barrel by means of the pin E (see Fig. 3) mounted in the grooves d and engaging in a similar groove in the side of the barrel. This trunnion band is provided 15 with two oppositely disposed arms, which are partly cylindrical, as at d', and terminate in inclined locking lugs or toggles d². The ends d³ of these toggles project beyond the cylindrical surface d', of the trunnion 20 member, and the distance between the parallel sides d⁴ of said toggles is less than the diameter of the trunnions, as shown most clearly in Figs. 10 and 11.

This trunnion band, it will be noted, is 25 detachably mounted on the gun, and by removing the pin E the said trunnion band and the parts carried thereby may be removed at a single operation. Such removal, however, would necessitate the removal of 30 the front sight C.

Revolutely mounted on the trunnions d' are two connecting pieces F and F', which may be called "socket pieces," to which the head pieces H and H', respectively, are 35 pivoted as at G. These head pieces carry the tubular legs I and I', as will be hereinafter more fully described.

Since the socket pieces F and F' are 40 merely rights and lefts, as also are the head pieces H and H' and the legs I and I', it will be sufficient to describe one only of each. Thus the socket piece F, shown in Figs. 5, 6, 8, 14 and 15, is provided with the transverse bore f adapted to turn freely on the corresponding trunnion d', and this bore f is provided with wings f' adapted to pass freely over the ends d³ of the toggle d² so that the parts may be conveniently assembled. This socket piece is provided with two lugs f² between which the web h² of the head piece H engages. These lugs f² are perforated, as at f³, to receive the hinge bolt G, see Figs. 5 and 9. The head piece H is provided with a downwardly projecting socket h adapted to receive the corresponding leg I, and is provided with perforations h' to receive fastening pins or bolts J whereby the leg is secured or fastened to the head piece.

Each head piece is provided with the web 60 h² adapted to pass between the corresponding lugs f² of the adjoining socket piece, and this web is perforated, as at h³, to permit the passage therethrough of the pivot G. Below this perforation h³ is a rounded socket h⁴ to 65 engage the ends of the lugs f² of the socket

piece F. The upper portion of the head piece is provided with a flat abutting surface h⁵ adapted to bear against the outer face of the corresponding socket piece when the parts are assembled, and this portion of the head piece is also provided with a socket h⁶ into which the toggle d² of the trunnion projects. This toggle fits loosely in the socket h⁶ so as to permit the requisite change in elevation of the gun. When the trunnion 75 band, the two socket pieces and the two head pieces are in the assembled relation, the parts are as shown in Figs. 5 to 9.

The legs I may be made of light material of sufficient strength, such as vanadium steel, 80 or aluminum steel alloy, and to one of these legs, as I', the brace K is pivoted as at k, and the free end of the brace is provided with a hook k' adapted to engage a pin L provided on the other leg I. A second pin 85 L' is also provided on the leg I to engage the hook k' when the two legs are brought up alongside the barrel, as will be hereinafter described.

Each leg is provided with a shoe M connected to the corresponding leg by a socket piece N or N'. These socket pieces N and N' are rights and lefts, but the shoes M are substantially the same construction, and each shoe is preferably in the form of an arcuate 95 plate, as shown in Figs. 1, 2 and 3; said plate having a substantially cylindrical lower face m and a rib m', which rib serves not only to engage in soft ground, but also serves to stiffen the shoe and prevent the same from 100 bending or becoming injured in use. The rib also permits the gun to recoil longitudinally, but tends to limit lateral vibration of the piece when being fired.

Owing to the width of the shoes, the legs 105 do not sink unequally into the ground, although the latter may be quite soft, as the usual pointed ends of such muzzle supports do; the stability therefore is much greater and traversing is very easy.

It will be noted that the shoes slip parallel to the vertical plane through the gun barrel, owing to the slipping of the shoes on the ground instead of vibrating during fire, as with other machine guns. The machine rifle 115 herein described recoils parallel to the ground when used with the muzzle rest, and returns to the initial position without disturbing the aim. Thus easy holding, good stability on any ground and accuracy of fire 120 are secured.

In assembling the parts shown in Figs. 1 to 15 inclusive, the trunnion band D is slipped over the gun barrel B before the front sight C is put on, and this trunnion 125 band is held in place by the movable locking pin E, then the two socket pieces F and F' are mounted on the corresponding trunnions, which may be readily done by turning the socket pieces so that the wings f' of the per- 130

foration f will register with the corresponding toggle d^2 , when the socket pieces may be slipped over said toggles and then turned to the engaging position, as shown in Fig. 7.

Now the webs h^2 of the corresponding legs are slipped into place between the lugs f^2 of the corresponding socket pieces, and the bolts J are inserted. The result will be that the head pieces will be hingedly connected to the trunnions and yet will be free to rotate thereon through the inter-position of the socket piece. The legs and shoes are normally attached to the head pieces and the brace K is normally attached to one of the legs, and when the parts are all assembled the legs may be spread apart by the brace, as shown in Fig. 2, in which case the bearing faces h^s of the head pieces H and H' will bear against the corresponding faces of the socket pieces F and F' , and the toggles will freely enter the sockets h^s in said head pieces.

In order to disassemble the parts, it will be sufficient to disengage the hook k' of the brace from the corresponding pin L , then swing each leg with the socket piece attached thereto until the toggle d^2 on the trunnion registers with the wings f' of the perforation f in the socket piece F , then remove the leg with the socket piece and shoe attached thereto, and this will leave the trunnion band fast on the gun. If it is desired to remove the trunnion band, push out the fastening bolt E , take off the front sight C and slip the trunnion band clear of the barrel.

The trunnion band may be left permanently on the barrel if desired, and the other parts separately stored away, or all of the parts may be carried with the piece if desired; and this is conveniently done by swinging up the two legs to the rear alongside of the barrel to the position indicated in dotted lines in Fig. 4, then passing the brace through the space between the barrel and the hand guard P to engage the hook k' over the pin L' of the opposite leg. The two legs with the shoes attached will then be held substantially parallel with the barrel. If desired to take off the shoes, this may be done by removing the fastening bolts O which connect the legs to the corresponding socket pieces carried by the shoes and prevent the shoes from being lost.

Each shoe should be preferably permanently attached to the legs, except when it is desired to remove same for purposes of repair or the like.

In the modification shown in Figs. 16 to 18, the trunnion band D' is provided with two trunnions d^o exteriorly screw-threaded to engage internal screw threads on the sleeves Q , which sleeves have down-

wardly projecting lugs q between which the web h^2 of the corresponding head pieces projects. These head pieces are made rights and lefts as shown at H^2 and H^3 , and it will be sufficient to describe one only.

Each head piece is provided with a socket to receive the corresponding tubular leg, and the leg is fastened to the corresponding head piece by means of one or more suitable bolts or pins J .

The web of the head piece is hinged to the corresponding sleeve by means of the pins G' and the top of each head piece is preferably provided with an engaging face h^s to engage a corresponding face on the sleeve and to prevent the leg from becoming unduly spread apart, the construction being shown in Fig. 18.

The legs are further braced by means of the brace K , hinged to one leg as at k and connected to the other leg by means of a hook k^2 engaging the pin L^2 . With this form of device the legs may be independently removed by simply unscrewing the corresponding sleeve with the leg attached from its trunnion band, and reapplied in the same way.

When carried with the gun, the legs may be swung substantially parallel to the axis of the bore and fastened to the gun, as hereinafter described, or in any other convenient way.

In the construction shown in Figs. 16 to 18, I have shown the trunnion band D' as provided with the downwardly projecting portion D^2 , having the gas passage d^o connected to the gas passage b^o from the barrel, the gas being conveyed to the motor piston cylinder R in the usual way.

With this construction it is possible to combine the trunnion band with the band provided for the gas passages referred to, thus resulting in a simplification of the parts.

It will be obvious that various modifications might be made in the herein described construction, and in the combination and arrangement of parts which may be used without departing from the spirit of my invention; and I do not mean to limit the invention to such details except as particularly pointed out in the claims.

Having thus described my invention what I claim and desire to secure by Letters Patent of the United States is:—

1. A muzzle support for guns of the character described, comprising a band secured to the barrel and provided with oppositely disposed trunnions, supporting legs hingedly connected to said trunnions, and curved shoes mounted on the free ends of said legs, substantially as described.

2. A muzzle support for guns of the character described, comprising a band secured to the barrel and provided with oppositely

4. disposed trunnions, supporting legs hingedly connected to said trunnions, a brace hinged to one leg, with means for detachably connecting said brace to the other leg, and 5 curved shoes mounted on the free ends of said legs, substantially as described.

3. A muzzle support for guns of the character described, comprising a band secured to the barrel and provided with oppositely 10 disposed trunnions, supporting legs hingedly connected to said trunnions, and shoes formed of arcuate metal bearing strips mounted on the free ends of said legs, substantially as described.

15 4. A muzzle support for guns of the character described, comprising a band secured to the barrel and provided with oppositely disposed trunnions, supporting legs hingedly connected to said trunnions, a brace hinged to one leg with means for detachably connecting said brace to the other leg, and shoes formed of arcuate metal bearing strips mounted on the free ends of said legs, substantially as described.

25 5. A muzzle support for guns of the character described, comprising a band secured to the barrel and provided with oppositely disposed trunnions, supporting legs hingedly connected to said trunnions, and shoes 30 formed of arcuate metal bearing strips, each provided with a circumferential rib on the outer face thereof, mounted on the free ends of said legs, substantially as described.

35 6. A muzzle support for guns of the character described, comprising a band secured to the barrel and provided with oppositely disposed trunnions, supporting legs hingedly connected to said trunnions, a brace hinged to one leg with means for detachably connecting said brace to the other leg, and shoes 40 formed of arcuate metal bearing strips, each provided with a circumferential rib on the outer face thereof, mounted on the free ends of said legs, substantially as described.

45 7. In a muzzle support for guns the combination with the gun barrel, of a trunnion band secured thereto and provided with rounded trunnions and diagonally-disposed toggles projecting beyond the ends of said 50 trunnions, and of a greater maximum than said trunnions, a perforated socket piece, in the form of a collar, provided with a perforation adapted to fit said trunnions, said perforation being provided with wings 55 adapted to permit the passage therethrough of the corresponding toggle, and a leg having a head piece hinged to said socket piece, substantially as described.

60 8. In a muzzle support for guns the combination with the gun barrel, of a trunnion band secured thereto and provided with rounded trunnions and diagonally-disposed toggles projecting beyond the ends of said 65 trunnions, and of a greater maximum diameter than said trunnions, a perforated

socket piece, in the form of a collar, provided with a perforation adapted to fit said trunnions, said perforation being provided with wings adapted to permit the passage therethrough of the corresponding toggle, 70 and said socket piece being also provided with downwardly projecting portions, and a leg having a head piece hinged to the downwardly projecting portion of said socket piece, with means for limiting the outward swing of said leg, substantially as described. 75

9. In a muzzle support for guns the combination with the gun barrel, of a trunnion band secured thereto and provided with 80 rounded trunnions and diagonally-disposed toggles projecting beyond the ends of said trunnions, and of a greater maximum diameter than said trunnions, a perforated socket piece, in the form of a collar, provided with 85 a perforation adapted to fit said trunnions, said perforation being provided with wings adapted to permit the passage therethrough of the corresponding toggle, and a leg having a head piece hinged to said socket piece, 90 with a shoe in the form of an arcuate plate provided with a longitudinal rib attached to the lower end of said leg, substantially as described.

10. In a muzzle support for guns the combination with the gun barrel, of a trunnion band secured thereto and provided with rounded trunnions and diagonally-disposed toggles projecting beyond the ends of said 95 trunnions, and of a greater maximum diameter than said trunnions, a perforated socket piece, in the form of a collar, provided with a perforation adapted to fit said trunnions, said perforation being provided with wings 100 adapted to permit the passage therethrough of the corresponding toggle, and said socket piece being also provided with a downwardly projecting portion, and a leg having a head piece hinged to the downwardly projecting portion of said socket piece, with means for 105 limiting the outward swing of said leg, with a shoe in the form of an arcuate plate provided with a longitudinal rib attached to the lower end of said leg, substantially as described. 110

11. In a muzzle support for guns the combination with the gun barrel, of a trunnion band secured thereto and provided with rounded trunnions and diagonally-disposed toggles projecting beyond the ends of said 115 trunnions, and of a greater maximum diameter than said trunnions, a perforated socket piece, in the form of a collar, provided with a perforation adapted to fit said trunnions, said perforation being provided with wings 120 adapted to permit the passage therethrough of the corresponding toggle, and a leg having a head piece hinged to the lower portion of said socket piece, said head piece having an upwardly extending bearing face adapted 125

to engage the upper portion of said socket piece, and to limit the outward swing of the lower end of said leg, substantially as described.

5 12. In a muzzle support for guns the combination with the gun barrel, of a trunnion band secured thereto and provided with rounded trunnions and diagonally-disposed toggles projecting beyond the ends of said 10 trunnions, and of a greater maximum diameter than said trunnions, a perforated socket piece, in the form of a collar, provided with a perforation adapted to fit said trunnions, said perforation being provided with wings 15 adapted to permit the passage therethrough of the corresponding toggle, and a leg having a head piece hinged to the lower portion of said socket piece, said head piece having an upwardly extending bearing face adapted 20 to engage the upper portion of said socket piece, and to limit the outward swing of the lower end of said leg, and the upwardly extending portion of said head piece being provided with a recess to receive the projecting 25 end of the corresponding toggle, substantially as described.

13. In a muzzle support for guns the combination with the gun barrel, of a trunnion band secured thereto and provided with rounded trunnions and diagonally-disposed toggles projecting beyond the ends of said 30 trunnions, and of a greater maximum diameter than said trunnions, perforated socket pieces, each in the form of a collar, provided 35 with a perforation adapted to fit said trunnions, said perforation being provided with wings adapted to permit the passage therethrough of said toggles, and said socket pieces being also provided with downwardly 40 projecting portions, and legs having head pieces hinged to the downwardly projecting portions of said socket pieces, said head pieces being each provided with an upwardly 45 extending bearing face adapted to engage the corresponding socket piece and to limit the outward swing of the lower end of the corresponding leg, substantially as described.

14. In a muzzle support for guns the combination with the gun barrel, of a trunnion band secured thereto and provided with rounded trunnions and diagonally-disposed toggles projecting beyond the ends of said 50 trunnions, and of a greater maximum diameter than said trunnions, perforated socket pieces, each in the form of a collar, provided 55 with a perforation adapted to fit said trunnions, said perforation being provided with wings adapted to permit the passage therethrough of said toggles, and said socket pieces being also provided with downwardly 60 projecting portions, and legs having head pieces hinged to the downwardly projecting portions of said socket pieces, said head 65 pieces being each provided with an upwardly extending bearing face adapted to

engage the corresponding socket piece and to limit the outward swing of the lower end of the corresponding leg, with shoes in the form of arcuate plates provided with longitudinal ribs attached to the lower end of 70 said legs, substantially as described.

15. In a muzzle support for guns the combination with the gun barrel, of a trunnion band secured thereto and provided with rounded trunnions and diagonally-disposed 75 toggles projecting beyond the ends of said trunnions, and of a greater maximum diameter than said trunnions, perforated socket pieces, each in the form of a collar, provided with a perforation adapted to fit said trunnions, said perforation being provided with wings adapted to permit the passage therethrough of said toggles, and said socket pieces being also provided with downwardly 80 projecting portions, legs having head pieces hinged to the downwardly projecting portions of said socket pieces, said head pieces being each provided with an upwardly 85 extending bearing face adapted to engage the corresponding socket piece and to limit the outward swing of the lower end of the corresponding leg, one of said legs being provided with a pair of projecting pins 90 spaced apart, and a brace hinged to the opposite leg and having a hook near its free end adapted to engage one or the other of said pins, as desired, substantially as described.

16. In a muzzle support for guns the combination with the gun barrel, of a trunnion 100 band secured thereto and provided with rounded trunnions and diagonally-disposed toggles projecting beyond the ends of said trunnions, and of a greater maximum diameter than said trunnions, perforated socket 105 pieces, each in the form of a collar, provided with a perforation adapted to fit said trunnions, said perforation being provided with wings adapted to permit the passage therethrough of said toggles, and said socket 110 pieces being also provided with downwardly projecting portions, legs having head pieces hinged to the downwardly projecting portions of said socket pieces, said head pieces being each provided with an upwardly 115 extending bearing face adapted to engage the corresponding socket piece and to limit the outward swing of the lower end of the corresponding leg, with shoes in the form of arcuate plates provided with longitudinal 120 ribs attached to the lower end of said legs, one of said legs being provided with a pair of projecting pins spaced apart, and a brace hinged to the opposite leg and having a hook near its free end adapted to engage one or 125 the other of said pins, as desired, substantially as described.

17. In a muzzle support for guns the combination with the gun barrel, of a trunnion band secured thereto and provided with 130

rounded trunnions and diagonally-disposed toggles projecting beyond the ends of said trunnions, and of a greater maximum diameter than said trunnions, perforated socket pieces, each in the form of a collar, provided with a perforation adapted to fit said trunnions, said perforation being provided with wings adapted to permit the passage therethrough of said toggles, and legs having head pieces hinged to said socket pieces, one of said legs being provided with a pair of projecting pins spaced apart, and a brace hinged to the opposite leg and having a hook near its free end adapted to engage one or the other of said pins, as desired, substantially as described.

18. In a muzzle support for guns the combination with the gun barrel, of a trunnion band secured thereto and provided with rounded trunnions and diagonally-disposed toggles projecting beyond the ends of said trunnions, and of a greater maximum diameter than said trunnions, perforated socket pieces, each in the form of a collar, provided with a perforation adapted to fit said trunnions, said perforation being provided with wings adapted to permit the passage therethrough of said toggles, and legs having head pieces hinged to said socket pieces, one of said legs being provided with a pair of projecting pins spaced apart, and a brace hinged to the opposite leg and having a hook

near its free end adapted to engage one or the other of said pins, as desired, with shoes in the form of arcuate plates provided with longitudinal ribs attached to the lower end of said legs, substantially as described. 35

19. A muzzle support for guns of the character described, comprising a band secured to the barrel and provided with oppositely disposed trunnions, supporting legs hingedly and revolvably connected to said trunnions, a brace hinged to one leg and provided with a hook near its free end, and pins secured to the other leg and spaced apart and adapted to engage said hook, respectively, when the legs are spaced apart and when swung alongside the barrel, substantially as described. 40

20. A muzzle support for guns of the character described, comprising a band secured to the barrel and provided with oppositely disposed trunnions, supporting legs hingedly and revolvably connected to said trunnions, a brace hinged to one leg and provided with a hook near its free end, and pins secured to the other leg and spaced apart and adapted to engage said hook, respectively, when the legs are spaced apart and when swung alongside the barrel, with shoes formed of 55 arcuate metal bearing strips mounted on the free ends of said legs, substantially as described. 60

CHARLES SUTTER.
